UNITED STATES PATENT OFFICE.

ROBERT E. FEE, OF MARION, INDIANA.

FLY-PAPER HOLDER.

No. 889,919.

Specification of Letters Patent.

Patented June 9, 1908.

Application filed October 9, 1907. Serial No. 396,578.

To all whom it may concern:

Be it known that I, ROBERT E. FEE, a citizen of the United States, and a resident of Marion, in the county of Brant and State of Indiana, have invented new and useful Improvements in Fly-Paper Holders, of which the following is a full, clear, and exact description.

This invention is an improved holder for retaining fly and other sticky papers in an extended position, whereby they cannot curl up, and may be moved from place to place without soiling the hands.

The object of the invention is to provide a device of this character of comparatively simple construction, which may be adjusted to hold sheets of fly paper of varying size and retain them under slight tension, also to provide for the suspending of the holder when not in use.

Reference is to be had to the accompanying drawings forming a part of this specification, in which similar characters of reference indicate corresponding parts in all the views.

Figure 1 is a plan of the holder in full lines when in its normal extended position, and in dotted outline when contracted as when removing or inserting the fly paper; Fig. 2 is a top edge view of the holder as when suspended against a wall or the like; Fig. 3 is a face view of a modified form of clamping member; Fig. 4 is a cross-section of the holder on the line 5—5 of Fig. 1, with the clamping members lifted from the frame and hooked, as preparatory to removing or inserting the fly paper; and Fig. 5 is a like section with the clamping members released and the fly paper clamped in position.

The invention comprises a wire frame composed of two sections slidably connected together; this connection being effected by making the cross-wires 5, forming a part of said frame, in two pieces, each piece being provided with an eye 6 in embrace with the other piece, as clearly shown in Fig. 1.

The frame further includes longitudinal wires 7 which are rigidly fixed in any suitable manner to the cross-wires 5 at their intersections. Two of the longitudinal wires 7, one in each section of the frame, are made by extending the ends of a bail or handle 8 which is provided with a central coil 9 operating as a spring to normally force the sections of the frame apart, and also serving as means for attaching a hook 10 for suspending the holder on a nail or other device when not in use.

The lower extremities of all of the wires 7 are bent to form hooks 11 for engaging the lower edge of the fly paper when the latter is seated within the frame. The margin of the paper is secured at the sides to the frame by clamps, each being carried by one of the frame sections, and comprising a longitudinal clamping wire 12 having hooks 13 formed at its opposite ends, which are coiled to form springs 13^a; the hooks and springs being constructed as an integral part of the top and bottom cross wires 5, and the springs acting to normally force the clamping wires to the frame.

The intermediate cross-wire 5 of the frame is extended beyond the frame at the opposite sides, and the extended portions of the wire off-set to form substantial hooks 14, each of the said hooks being adapted to be engaged with a loop 15 having the opposite ends thereof bent into embrace with the clamping-wire 12. The loops 15 are angularly-turned over longitudinal wires 16, connecting the hooks 13 of the clamping members together, and are further connected to the wires 16 and to the outer longitudinal wires 7 by short wires 17, which not only reinforce the clamping members, but prevent the loops from sliding longitudinally thereon. As will be observed from Fig. 5, the position of the loops 15 is such when the clamping wires are pressed to the frame by the springs 13 that they are located slightly above the off-set or hooked ends 14 of the cross-wire 5, whereby when the clamping wires are lifted against the tension of the springs and the loops 15 engaged behind the hooks 14, the clamps will be disposed in the position shown in Fig. 4.

When inserting the fly paper within the holder, the clamping members are secured in inoperative position as represented in Fig. 4, and the fly paper passed under the hooks 11, after which the sections of the frame are sprung together against the tension of the bail until the margin of the paper at the opposite sides passes under the clamping wires. The loops 15 are then released, permitting the springs of the clamping members to force the clamping wires into firm contact with the paper. The tendency of the bail and its spring 9 will also operate to force the two sections of the frame outwardly and keep the paper stretched out under slight tension.

In Fig. 3 I have shown a modified form of clamping member which is in all respects the same as that shown in Fig. 1, except that the

clamping-wire 12^a, corresponding to the wire 12, instead of being made continuously straight is provided with a plurality of off-sets 12^b; these off-sets only engaging the paper when the latter is clamped.

The invention as shown and described while being the preferred construction of my improved holder may be obviously modified in numerous minor particulars, and I consider I am entitled to such changes as fall within the scope of the appended claims.

Having thus described my invention, I claim as new and desire to secure by Letters Patent:

15 1. A fly paper holder composed of two sections slidably connected together, means for clamping the edge of the paper carried by said sections, and means normally tending to separate said sections, whereby the paper 20 will be held under tension.

2. A wire frame composed of two sections adjustably connected together, means for suspending the frame forming a part of each section and operating to force them apart, 25 and clamping means carried by the opposite sides of the frame.

3. A wire frame composed of two sections made up of cross-wires and longitudinal wires joined at their intersections, each of 30 said cross-wires being made in two pieces with an eye formed on each piece in embrace with the other piece, whereby the sections may be adjusted to and from each other, and clamping means carried by each 35 section.

4. A wire frame composed of two sections adjustably connected together and having hooks at one end thereof, a bail for suspending the frame operating to separate said sections, and a clamp carried on each section at 40 the opposite sides of the frame.

5. A fly paper holder comprising a wire frame composed of longitudinal wires and cross-wires connected together at their inter-

sections, each of said cross-wires being made 45 in two pieces adjustably connected together and dividing the frame into two sections, a clamping wire connected to the cross-wires of the frame on each section, and means for normally forcing the clamping wires toward 50 the cross-wires.

6. A fly paper holder consisting of a frame composed of cross-wires and longitudinal wires, each of said cross-wires being composed of two pieces adjustably connected 55 together, dividing the frame into two sections, hooks formed at one end of the longitudinal wires for engaging the paper, clamps carried by the opposite sides of the frame for clamping the edges of the paper, and a bail 60 for suspending the frame normally tending to separate said sections, whereby the paper is held under tension.

7. A fly paper holder comprising a wire frame having clamps formed at the opposite 65 sides thereof provided with means normally forcing them to the frame, and means for holding the clamps in inoperative position against the tension of the first-named means.

8. A fly paper holder comprising a frame 70 consisting of cross-wires and longitudinal wires joined together at their intersections, one of said cross-wires having extended ends, clamps having springs normally forcing them into contact with the frame at the opposite sides thereof, and means attached to each clamp adapted to engage the extended end of one of said cross-wires and hold the clamp away from the frame against the tension of its spring.

In testimony whereof I have signed my name to this specification in the presence of two subscribing witnesses.

ROBERT E. FEE.
